UNITED STATES PATENT OFFICE.

WINFIELD E. RANDALL, OF EYOTA, MINNESOTA.

CHICKEN ROOST.

Application filed August 31, 1922. Serial No. 585,463.

To all whom it may concern:

Be it known that I, WINFIELD E. RANDALL, a citizen of the United States, residing at Eyota, in the county of Olmsted and 5 State of Minnesota, have invented certain new and useful Improvements in Chicken Roosts; and I do declare the following to be a full, clear, and exact description of the invention, such as will enable others skilled 10 in the art to which it appertains to make and use the same.

This invention relates to an improved chicken roost of the class having a receptacle for a quantity of insecticide to prevent 15 accumulation of vermin thereon.

One object of the invention is to generally improve upon roosts of this class by providing one of comparative simplicity which is practical, sanitary, inexpensive to 20 manufacture, and such in construction that it will retain the disinfectant liquid for a longer period than is done with prior patented and marketed roosts with which I am familiar.

Speaking more specifically, it is another and a very important object of the invention to provide a roost which embodies relatively small and large compartments, the large compartment being intended to contain 25 suitable absorbent material, while the other compartment is intended to be filled with liquid insecticide which passes therefrom through openings in the partition to slowly but thoroughly saturate the absorbent material with the insecticide.

Other objects and advantages of the invention will be apparent during the course of the following description.

In the accompanying drawing forming a part of this specification and in which like numerals are employed to designate like parts throughout the same:

Figure 1 is a plan view of a roost constructed in accordance with this invention.

Figure 2 is a similar view with the cover removed.

Figure 3 is a longitudinal section taken on the line 3—3 of Fig. 1.

Figures 4 and 5 are transverse sections taken on the lines 4—4 and 5—5 respectively of Fig. 1.

Figure 6 is a longitudinal sectional view of a slightly modified form of the invention.

Figure 7 is a top plan view with parts removed to disclose the construction more clearly.

In the drawing, the reference character 1 designates generally an elongated strip of wood which is formed in its upper side with a longitudinal channel terminating adjacent the opposite ends thereof. This channel is comparatively deep and is divided by a longitudinal partition 2 into separate compartments 3 and 4 respectively. It is to be noted that the partition is arranged at a point so as to render the compartment 3 comparatively narrow and the remaining one comparatively wide. The wide compartment is intended to be filled with suitable absorbent material 5. In practice, it has been found that sawdust may be advantageously used. The narrow compartment is intended to be filled with liquid insecticide and the latter is permitted to flow from this compartment into the wide compartment through slots or openings 6 formed in the partition, whereby to saturate the absorbent material in the last named compartment. In practice, there will be one or two small openings in the partition if the roost is not made too long. This will permit the liquid to flow slowly from the narrow compartment into the wide one and to thus thoroughly saturate the absorbent material. The number of liquid passages in the partition may be increased if necessary or desired. To complete the roost, a wooden cover plate 7 is nailed to the top of the wooden strip to close the compartments. As clearly shown in the drawing, this cover is formed adjacent its ends at points directly over the narrow channel 3 with filling openings 8 through which insecticide is introduced. Should it be desired, these openings may be closed by suitable means.

The form of the invention so far described is intended to be used mostly when short roosts are desired. However, since in many instances roosts of greater length will be preferred, it may be advisable to vary the construction slightly as disclosed in the modified form of the invention shown in Figs. 6 and 7. Reference being had to these figures, it will be seen that the reference character 1^a designates an elongated wooden bar which is likewise formed in its upper side with a plurality of channels divided and longitudinally spaced from each other by short transverse partitions 9. Each channel is divided into narrow and wide compartments 3^a and 4^a respectively, and communication is afforded between the

two compartments through openings 6^a. Each channel is closed by a cover 7^a which is secured in place in any suitable way and as before indicated, this cover is equipped 5 with a filling opening 8^a through which the disinfecting liquid is introduced.

In practice, it is apparent that liquid insecticide is introduced into the narrow compartment of the roost through the filling 10 openings in the cover. The narrow compartment is filled with this liquid and the latter escapes slowly through the passages in the dividing partition between the compartments and gradually and thoroughly 15 saturates the sawdust or other absorbent material in the large compartment.

It is evident from the foregoing description and drawing that I have evolved and produced a unique chicken roost which is 20 practical and advantageous over well known roosts of this character now on the market. Emphasis is to be laid on the fact that the characterizing feature of the invention is the provision of a compartment in which the 25 disinfecting liquid is placed to pass from it through openings in a partition into a large compartment containing suitable absorbent material. Stress is laid upon this point in view of the fact that much time 30 will be saved in supplying the roost with the disinfectant liquid. It is obvious that on large chicken farms where thousands of roosts are employed, much time is consumed in disinfecting them due to the fact that they 35 must be replenished frequently. Therefore, I have conceived the idea of placing the absorbent material in the compartment for retaining the insecticide for a considerably long period of time. It may be 40 mentioned here that I am fully aware of the fact that it is not broadly new to employ absorbent material, nor is it new to provide a roost having compartments of a nature similar to mine. However, so far as I 45 have been able to determine, it is novel to produce a roost having the narrow and wide compartments wherein the liquid is introduced into the narrow one to flow through openings in the partition into the wide one 50 to saturate the absorbent. It is clearly evident that this is important in that it will mean a great saving of time because it will only be necessary to simply fill the narrow compartment in one roost and the absorbent 55 material therein will become automatically

saturated. Where the disinfectant is introduced directly into the compartment containing the absorbent material, much time is wasted in awaiting thorough saturation thereof, before going to the next roost to 60 supply it with disinfectant. This disadvantage is entirely eliminated with my unique roost.

By carefully considering the description in connection with the drawings, persons familiar with devices of this class will doubtless be able to obtain a clear understanding of the invention. Therefore, a more lengthy and detailed description is deemed unnecessary. 70

Since probably the best results may be obtained with the construction and arrangement herein shown and described, this is taken as the preferred embodiment of the invention. However, I wish it to be understood that minor changes coming within the scope of the invention as claimed may be resorted to if desired. 75

I claim:

1. A chicken roost embodying an elongated body formed with a longitudinal channel opening through the top thereof and having a longitudinal apertured partition in the channel dividing it into small and large communicating compartments, the large 80 compartment being intended to hold absorbent material for the insecticide and the small compartment being intended to be filled with the liquid insecticide to thoroughly and gradually saturate the absorbent by permitting passage of the liquid 85 through the aperture. 90

2. A chicken roost comprising an elongated body having a channel formed therein and opening through its top and provided with a longitudinal apertured partition arranged in the channel to divide it into relatively wide and narrow compartments, the wide compartment being intended to contain a quantity of insecticide absorbent material, and the other compartment being intended to be filled with an insecticide to permit it to pass through the passages in the partition into the wide compartment, and a cover for 100 said compartments, said cover being provided with a filling opening arranged directly over the narrow compartment. 105

In testimony whereof I have hereunto affixed my signature.

WINFIELD E. RANDALL.
